Primary Examiner — R. Johnson(74) *Attorney, Agent, or Firm* — Rondaus PLLC; George Liu(57) **CLAIM**

The ornamental design for a multi-effects controller, as shown and described.

DESCRIPTION

FIG. 1 is a top perspective view of a multi-effects controller showing our new design;

FIG. 2 is a bottom Perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion taken at line-9 in FIG. 1; and,

FIG. 10 is an enlarged view of the portion taken at line-10 in FIG. 7.

The broken lines in the drawings illustrate the portions of the multi-effects controller which form no part of the claimed design. The dash dot lines in FIGS. 1, 7, 9 and 10 are for the purpose of illustrating the enlarged view indicators and form no part of the claimed design.

1 Claim, 10 Drawing Sheets(56)
